UNITED STATES PATENT OFFICE.

ARNOLD NACKE, OF PHILADELPHIA, PENNSYLVANIA, ASSIGNOR OF ONE-HALF TO ISIDOR KITSEE, OF PHILADELPHIA, PENNSYLVANIA.

PLATFORM FOR POWER-MOTORS.

No. 812,444.

Specification of Letters Patent.

Patented Feb. 27, 1906.

Application filed March 25, 1905. Serial No. 252,058.

To all whom it may concern:

Be it known that I, ARNOLD NACKE, of the city and county of Philadelphia, State of Pennsylvania, have invented certain new and useful Improvements in Platforms for Power-Motors (Case No. 242,) of which the following is a specification.

My invention relates to an improvement in platforms for power-motors. Its object is to lessen the vibration of such power-motors on buildings in which they are placed.

Referring to the drawings, Figure 1 is a side elevation, partially in section, of the platform and the power-motor (here shown as a gas-engine) placed thereon. Fig. 2 is a front elevation, partially in section, showing the platform with the gas-engine placed thereon.

In the figures, A is the platform as an entirety; B, the power-motor placed thereon. The platform embraces the base proper, C, resting with one end on the floor D. This base is secured with the aid of the upright E and the swiveled bars E' and E² to the beam or joist of the ceiling F. Of the swiveled bars E' and E² one exerts a downward pressure on the base and the other two exert an upward pressure on the base, as is signified by the arrows in the drawings, this for the purpose of holding the base rigid. In constructing this platform I found that whereas if this platform is entirely free from the floor the pressure and vibration on the ceiling are very great the addition of a resting-point, no matter how slight, not only lessens the strain on the ceiling, but also lessens the vibration to a great extent. I also found that when, as is usually the case, the base is held only by the straight uprights to the joist of the ceiling or by uprights which only exert a pressure in one direction, the required rigidity is never attained; but when, as in my invention, one of the bars exerts a pressure so as to force the platform downward and the other exerts a pressure so as to force the platform upward a degree of rigidity is reached not otherwise attainable.

Instead of resting the platform-base directly on the floor proper it is preferred that between the floor and the base of the plat-

form a yielding material—such, for instance, as a heavy spring or heavy piece of rubber—should be placed.

Having now described my invention, what I claim as new, and desire to secure by Letters Patent, is—

1. A platform for power-motors embracing the base proper, uprights securing said base to the joist of the ceiling of the room in which the platform is placed, a swivel-brace forcing the platform upward and a swivel-brace forcing the platform downward, a floor and means to support part of said platform on said floor.

2. In combination with a platform on which a power-motor is placed, means to keep said platform suspended between the floor and ceiling of the space in which said platform is placed, swiveled means to force said platform upward and swiveled means to force said platform downward and means to support part of said platform on the floor of said space.

3. Means to lessen the vibration of a power-motor on the building in which it is placed, said means embracing a platform suspended from the ceiling, means to force said platform upward, means to force said platform downward, and means to support part of said platform on the floor.

4. In combination with a power-motor, a platform for said motor, uprights securing said platform to a ceiling, and in further combination with means to secure part of said platform to the floor.

5. In combination with a power-motor, a platform whereon said motor is placed, uprights securing said platform to a ceiling, and in further combination with adjustable means, one to force the platform upward and the other to force the platform downward.

In testimony whereof I hereby sign my name, in the presence of two subscribing witnesses, this 7th day of March, A. D. 1905.

ARNOLD NACKE.
